UNITED STATES PATENT OFFICE.

JENNIE R. McMATH, OF SAN DIEGO, CALIFORNIA.

CLOTHESPIN CARRIER.

Application filed April 5, 1922. Serial No. 549,758.

To all whom it may concern:

Be it known that I, JENNIE R. McMATH, a citizen of the United States, residing at San Diego, in the county of San Diego and 5 State of California, have invented a certain new and useful Clothespin Carrier, of which the following is a specification.

My invention relates to a clothespin carrier, particularly to a means for carrying 10 the pins while hanging the clothes on or removing the same from the line and the objects of my invention are: first, to provide a device of this class by which the person hanging up clothes on or removing clothes 15 from the line does not have to stoop, bend over or reach down to get the pins for securing the clothes to the line or to replace the pins in the receptacle when removing the same from the line; second, to provide 20 a device of this class in which it is not necessary for the user of this device to hold a number of pins in the mouth or in the hand, thus reducing to a minimum the usual inefficiency or the dropping of clothes; 25 third, to provide a device of this class which is always in close proximity to the person hanging up clothes and which can readily be shifted along as desired; fourth, to provide a device of this class which will free 30 the user thereof from lugging unnecessary weight around on the body; fifth, to provide a device of this class which is conveniently supported by the clothesline at the place needed; sixth, to provide a carrier of this 35 class in which the receptacle thereof may readily be removed from its support for cleansing or washing the same; seventh, to provide a novelly constructed pin carrier, and eighth, to provide a device of this class 40 which is very simple and economical of construction, durable, efficient and which will not readily deteriorate or get out of order.

With these and other objects in view as will appear hereinafter my invention consists of certain novel features of construction, combination and arrangement of parts and portions as will be hereinafter described in detail and particularly set forth in the appended claims reference being had to the 45 accompanying drawings and to the characters of reference thereon which form a part of this application in which:

Figure 1 is a perspective view of my clothespin carrier suspended from a clothes- 50 line; Fig. 2 is a front view thereof looking into the opening of the same and Fig. 3 is

a perspective view of the supporting ring of my device.

Like characters of reference refer to similar parts and portions throughout the several views of the drawings.

The ring 1, and the receptacle 2 constitute the principal parts and portions of my clothespin carrier.

The ring 1 is preferably circular in shape 65 provided with an open hook 1^a at right angles to the plane of the ring and opening outwardly therefrom adapted to support said ring on a clothesline and the like. Said ring is also provided with another open hook 70 1^b as part of the ring and adapted to hook around the base portion of the first mentioned hook 1^a. The receptacle 2 is preferably made of some flexible fabric material in the shape of a bag, preferably as shown, 75 with an opening 2^a at one end thereof. A heading 2^b adapted to receive the ring portion of the ring member 1 is provided at the opening of the receptacle and is formed by turning over the end of the material surrounding the opening and stitching the same to the other portion of the receptacle. There is provided in the heading of said receptacle an opening 2^c at one side thereof so that the ring member, when unhooked, may be easily 80 inserted through said heading and again hooked together after being passed around or through the heading. Thus a means is provided whereby the receptacle may be conveniently removed and replaced on said 85 ring.

My clothespin carrier is so shaped and suspended that the clothespins therein will not fall out of the receptacle thereof and will permit easy and convenient access to 90 the pins at all times.

Though I have shown and described a particular construction, combination and arrangement of parts and portions I do not wish to be limited to this particular construction, combination and arrangement but desire to include in the scope of my invention the construction, combination and arrangement substantially as set forth in the appended claims.

Having thus described my invention what I claim as new and desire to secure by Letters Patent is:

1. In a device of the class described, a fabric receptacle provided with an opening 110 at one end and with a heading at said open end, and a ring within said heading pro-

vided with a loop on one end and a supporting hook on the other end and provided with an angular bend adjacent said hook adapted to engage said loop.

5. 2. In a device of the class described, a fabric receptacle provided with an opening at one end and a heading surrounding said

opening and a detachable ring in said heading provided with supporting means and hook means to connect the ends of said ring. 10

In testimony whereof, I have hereunto set my hand at San Diego, California, this 29th day of March, 1922.

JENNIE R. McMATH.
